Primary Examiner—Ted ShoomanAssistant Examiner—C. Tuttle[57]*CLAIM

The ornamental design for a hand-held rechargeable makeup and hair color mixer, as shown and described.

DESCRIPTION

FIG. 1 is a right side elevational view of the hand-held rechargeable makeup and hair color mixer showing my new design, the opposite being a mirror image of the side shown; FIG. 2 is a rear elevational view thereof; FIG. 3 is a front elevational view thereof; FIG. 4 is a top plan view thereof; and, FIG. 5 is a bottom plan view thereof.

The undisclosed surfaces of the handle and blades follow the contours of the sides shown; and the cord is shown partially broken away in the various views to indicate indeterminate length.
